UNITED STATES PATENT OFFICE.

CLARENCE L. McCLELLAN, OF ARANSAS PASS, TEXAS.

TUBE-COMPRESSING DEVICE.

1,033,717.

Specification of Letters Patent. Patented July 23, 1912.

Application filed April 8, 1911. Serial No. 619,756.

To all whom it may concern:

Be it known that I, CLARENCE L. McCLELLAN, a citizen of the United States, residing at Aransas Pass, in the county of 5 San Patricio and State of Texas, have invented new and useful Improvements in Tube-Compressing Devices, of which the following is a specification.

The invention relates to an attachment for 10 a bathing apparatus, and more particularly to the class of tube compressing devices.

The primary object of the invention is the provision of a device of this character in which the water flow may be controlled 15 through a siphon tube from a water receptacle, when used with a shower or bathing device.

Another object of the invention is the provision of a tube compressing device 20 which may be conveniently packed and stored within a small space, when not in use, thereby making it useful for persons traveling.

A further object of the invention is the 25 provision of a device of this character which is simple in construction, thoroughly reliable and efficient in purpose, and inexpensive in manufacture.

The device is designed to be used in combination with a suitable water receptacle, a siphon, a water spray or other device, and a waste water sheet, as will be hereinafter 30 more fully described.

In the drawings: Figure 1 is a perspective 35 view of a bathing apparatus, showing the device constructed in accordance with the invention applied thereto. Fig. 2 is a fragmentary side elevation of a water receptacle, such as a pitcher, showing the siphon tube 40 supported thereon, with the device applied thereto. Fig. 3 is a vertical sectional view through the tube compressing device.

Similar reference characters indicate corresponding parts throughout the several 45 views of the drawings.

Referring to the drawings by numerals, there is shown a water-proof or rubber sheet 50, having secured at its corners in any suitable manner the ends of loop-like handles 11 which permit the carrying of the sheet when burdened with a quantity of water used for bathing purposes, it being seen that upon raising the sheet by the handles 11, the waste water caught therein will be held 55 thereby and readily emptied. This sheet

10 is spread upon the floor or other foundation, so as to overlie a strap 12 of the ordinary well-known construction, the same being arranged in a ring-like manner beneath the sheet, so that the latter will form a 60 waste water depository, as is clearly shown in Fig. 1 of the drawings.

At the required elevation above the sheet 10, and to one side of the same, is suitably supported an ordinary water pitcher 14 65 forming a water receptacle, the same having the usual handle 15, to which is attached the tube compressing device, presently described.

The tube compressing device comprises an 70 arcuate-shaped base 17 having near opposite ends hook-like supporting ears 18, in which is engaged a flexible siphon tube 19, one end of which extends into the pitcher 14, the base 17 being formed with a central 75 extension 20 which is provided with spring fingers 21, the latter detachably embracing the handle 15 of the said pitcher 14 for the mounting of the device thereon, as shown in Fig. 1 of the drawing. 80

Loosely connected to the base 17 is a lever 22, one end of which is loosely connected, at 23, to the said base, and this lever is adapted to overlie the tube 19 to compress the same, and when in this position will be 85 brought into locked position with a hook-like keeper, lip or tongue 24 struck out from the extension 20 on the base. This lever is normally thrown out of engagement with the tube 19, so that water may siphon there-through from the pitcher for bathing purposes. 90

Detachably engaged in the remaining end of the siphon tube 19 is a shower attachment, comprising a flexible neck yoke or 95 loop 29, the same being provided with suitable perforations to permit the water to be discharged therefrom, when placed about the neck of a person.

From the foregoing, taken in connection 100 with the accompanying drawings, it is thought that the construction and operation of the invention will be readily understood, without requiring a more extended explanation. 105

What is claimed is:

A tube support, comprising an arcuately shaped plate having a medial resilient clip extension at one edge adapted for detachable engagement with a support, outturned 110

hook-like ears projecting from one edge of the plate near opposite ends thereof, an out-struck keeper tongue on the said extension, and a lever hinged to the plate in alinement with the extension and engageable in the keeper tongue for contracting a tube to cut off the fluid supply therethrough.

In testimony whereof I affix my signature in presence of two witnesses.

CLARENCE L. McCLELLAN.

Witnesses:

M. C. BILLINGS,

O. C. McLEOD.
